UNITED STATES PATENT OFFICE

2,541,772

STRIPPER PLATE WITH LOCK NUT

Vene T. Lockard, Gladstone, Mich., assignor of
one-half to Agnes M. Gerue, Escanaba, Mich.

Application December 8, 1949, Serial No. 131,879

3 Claims. (Cl. 164—110)

1

This invention relates to a stripper plate with a lock nut, designed primarily for use under the stripper plate on dies, although it is entirely possible that other uses of the nut may suggest themselves.

By way of background, it may be noted that in the die making art, it is well known that a decided inconvenience and annoyance stems from the inability of the die maker to lock stripper bolts from the face of the die, since many of these are located in the die where no wrench can be used. Additionally, conventionally shoulder bolts are used, this calling for expensive and exacting work, in that shoulders and counterbores for said bolts must be exact. As the die is ground down, the shoulder bolts must be shimmed down, as they become too long. Additionally, in the use of shoulder bolts, the bolt tends to work loose, in view of which the die must be removed from the press to tighten the bolts. Obviously, the expense of grinding rises considerably where a die must be dismantled to be ground. Additionally, all bolts and holes must be numbered, since all must be returned to their exact previous locations.

In accordance with the present invention, it is proposed to use a specially designed lock nut under the stripper plates, by the use of which standard hollow head cap screws may be used as stripper bolts instead of the special expensive shoulder bolts.

It is further proposed, by the use of said lock nut, to allow the grinding of large dies without the necessity of dismantling the stripper plate with all its bolts, springs, etc.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Fig. 1 is a fragmentary section taken through a stripper plate and die shoe showing the invention as used in the die.

Fig. 2 is a section taken substantially on line 2—2 of Fig. 1.

Fig. 3 is a fragmentary section taken through the stripper plate showing a modified arrangement.

Fig. 4 is a top plan view of a templet or drill jig embodied in the invention.

2

Fig. 5 is a side elevational view of said templet. Referring to the drawings in detail, 5 is a conventional die shoe, and 6 the conventional stripper plate used in association therewith.

Formed in the die shoe is the smooth-walled bolt hole 7 formed with the counterbore 8, and extending into said bolt hole 7 is the standard hollow head cap screw 9 formed with the head 10 seated in the counterbore 8. The shank of the cap screw 9 has the threaded end 10' threaded into the threaded opening 11 formed in the stripper plate 6 and threadable on said end 10' of the bolt or cap screw 9 is the lock nut formed in accordance with the invention, the body of this nut being formed at one end with the shroud 12 and at the other end with the circumferential series of gear teeth 13.

For the purpose of rotating the lock nut, I provide the pinion rod 14 extending through the bearing opening 15 formed in the stripper plate 6, the portion of said pinion rod 14 that extends below the bearing opening being formed with the circumferential series of gear teeth 16 meshing with the gear teeth 13 of the lock nut. The lower end of said pinion rod 14, as readily seen from Fig. 1, seats upon the shroud 12, so as to prevent the pinion rod 14 from moving downwardly through its bearing opening any more than is desired.

For the purpose of convenience in rotating the pinion rod 14, the upper end of the pinion rod can be formed with a transverse opening in which is slidable the handle 17.

Referring now to the form of the invention illustrated in Fig. 3, the stripper plate is here designated 18, and is formed with the threaded opening 19 receiving the cap screw 9. In this form of the invention, there is no difference in the construction of the cap screw, lock nut, and pinion rods, and the main difference resides in the provision of a pair of bearing openings 21 rather than a single bearing opening, so that two pinion rods 14 can be used, one extending downwardly through the stripper plate on either side of the threaded opening, and these engaging and meshing with the gear teeth of the lock nut at opposite sides of said lock nut. This provides extra locking power.

Referring now to Figs. 4 and 5, I have here illustrated a templet or drill jig used to properly locate the bearing opening 15 relative to the threaded opening 11 of the stripper plate 6. This templet or drill jig is provided with an oblong body 22 adapted to rest upon the upper surface 55 of the stripper plate 6, this oblong body being

formed at one end with a smooth walled opening 23 of a diameter equalling the diameter of the bearing opening 15, while at the other end, the oblong body is formed with an opening 24 in which is drive-fitted a stud 25 formed on the upper end of a pilot plug 26 the diameter of which equals the diameter of the threaded opening 11 of the stripper plate. In other words, the plug 26 is simply inserted in the opening 11, and this locates the place at which the bearing opening 15 should be drilled. 10

In use, the parts appear as in Fig. 1. As may be noted, the key or rod 14 is inserted through the bearing opening 15, engaging the gear teeth 13. The handle 17 is now rotated, and this loosens the lock nut. The stripper bolt 9 may now be tightened with a standard wrench to bring the stripper plate down below the face of the die for grinding of said die.

After the die is ground, the stripper bolts may be released enough to obtain the proper adjustment of the stripper plate, after which the bolts are locked in position by tightening of the lock nut with the wrench 14.

It has been found that the formation and relative arrangement of parts illustrated and described will eliminate all the difficulties noted at the beginning of this description.

What is claimed is:

1. The combination, with a stripper plate and die shoe, of a cap screw extending through the die shoe and threaded in the stripper plate, the stripper plate having a smooth-walled opening adjacent said cap screw, a toothed lock nut threaded on the cap screw below the stripper plate, and a toothed rod extending through said opening of the stripper plate and meshing with the lock nut for rotating said lock nut. 30

2. The combination, with a stripper plate having a threaded opening and a smooth opening, a die shoe spaced from the stripper plate and having a smooth opening registering with the threaded opening, and with a cap screw extending through the smooth opening of the die shoe and threaded in the threaded opening of the stripper plate, of a lock nut threaded on the cap screw and disposed between the stripper plate and die shoe, the lock nut having one side 40

5 formed with a shroud constituting a wrench stop, the other side of said cap screw being formed with a circumferential series of gear teeth, and a pinion rod extending through the smooth opening of the stripper plate and having teeth meshing with the teeth of the lock nut, said pinion rod seating on the shroud.

3. The combination, with a stripper plate and die shoe spaced apart, said stripper plate having a threaded opening and a smooth-walled opening adjacent said threaded opening, the die shoe having a counterbored smooth-walled opening, and with a cap screw seated in the counterbored opening of the die shoe and threaded in the threaded opening of the stripper plate, of a circular lock nut threaded on the cap screw, one end of said lock nut being formed with a circumferential series of gear teeth, the other end of said lock nut being formed with an annular shroud constituting a wrench stop, an elongated pinion rod extending through the smooth-walled opening of the stripper plate, that portion of the pinion rod extending through the stripper plate being formed with a circumferential series of spur gear teeth, and means at the other end of the pinion rod for rotating said pinion rod after the gear teeth of the rod are in mesh with the teeth of the lock nut, said shroud constituting a stop for the first-named end of the pinion rod.

VENE T. LOCKARD.
